UNITED STATES PATENT OFFICE

2,180,308

FOUNTAIN COMB

Moses Marton, New York, N. Y.

Application October 22, 1935, Serial No. 46,088

18 Claims. (Cl. 132—13)

The invention relates to fountain-combs embodying means for holding and discharging liquids or semi-liquids used in the treatment of the scalp or the hair.

5 The main object of the invention is the provision of a comb which externally, as regards size, shape, weight and convenience of handling, is not unlike the ordinary comb; the interior however is channelled and provided with simple automatic mechanism by means of which mechanism one can fill the reservoir and discharge its contents, in whole or in part regulated according to desire.

With these and other objects in view the invention presents a new and novel construction and combination of parts described and shown in the accompanying drawing forming a material part of this disclosure and in which,

20 Fig. 1 is a longitudinal section taken through my improved comb.

Fig. 2 is a longitudinal section taken through my improved comb showing an embodiment of my invention.

25 Fig. 3 is an end view of my comb taken at 3—3, Fig. 1.

Fig. 4 is a fragmentary sectional view of my valve stud taken on line 4—4, Fig. 2.

Fig. 5 is a longitudinal sectional view of my valve stud.

30 Fig. 6 is a fragmentary elevational view showing an embodiment of my invention.

Referring now to Fig. 2, of the drawing, 10 represents a channelled dispensing comb in which 11 is the reservoir, the forward portion of which 12 holds the liquid or semi-liquid (to be dispensed) and the rearward portion of which has automatic mechanism for filling the reservoir and/or emptying it of its contents. In continuation with the forward part 12 of the reservoir there is a stud 13 (details of which are shown in Fig. 5), having its outer portion, towards the forward end of the comb, solid, and its inner portion adjacent to the reservoir channelled longitudinally at 134, forming a continuation of the reservoir. There

45 are several apertures 131, 132, 133 (Fig. 4), of variable size, in the wall of the channelled part of the stud. By turning the stud one way or another (the predetermined positions being marked on the exterior surface of the head of the stud) 50 the apertures may be brought in or out of line with the connecting duct 111, which leads to the distributing channel 19, thus regulating the rate of discharge. When said apertures 131, 132, 133, are turned out of registration with said duct 111, 55 it is naturally blocked so that no liquid may flow

therethru. The stud 13 is removable for the purpose of filling the reservoir, (by pouring the liquid into the reservoir or sucking it thereinto after the manner of a syringe). The distributing channel 19, is usually of much smaller diameter than the reservoir, with which it communicates by way of the connecting duct 111, and stud 13, as described above. Through a number of apertures 131, in its wall, the distributing channel is also in communication with a series of discharge channels 201, which run through the comb's teeth 29, and open at the termination of the teeth or at any desirable place along their surface.

The operating mechanism of the comb consists of a piston or plunger 14, preferably cylindrical in shape. The diameter of the piston corresponds with the diameter of the reservoir 11, in which it moves longitudinally one way or another, in a manner similar to the plunger of a syringe. The forward end of a coiled extensible spring 15 is 20 firmly attached to the piston as at 141, while the other end 151 rests against the bottom of the reservoir. At the juncture of the piston and spring 141 there is also attached one end of a pull chain or cord 17. The cord passages through the 25 channel formed by the coils of the spring and emerges from the reservoir through a small aperture 18, at the backward or handle part of the comb. A few inches of length of this cord hangs outside the comb to provide a good grip for pulling it. When the cord is pulled it causes the spring to contract bringing the piston towards the bottom of the reservoir (in this position the reservoir is filled; either by suction or by pouring the liquid in, having first removed the stud 13). 30 When the cord is released it automatically releases the spring permitting it to expand and push the piston forwards toward the stud 13. The stud blocks the expulsion of the liquid from the reservoir if its apertures 131, 132, 133 are out 35 of alignment with the connecting duct 111 of the distributing channel 19 or permits a faster or slower rate of discharge according to whether a larger or smaller apertures is brought in alignment.

45 The mechanism described above, because of its simple construction and operation also because it is composed of very few parts, so that barely anything can break down, is considered best suited for general use. However there are special 50 needs in beauty and barber establishments requiring the use of larger quantities of liquid than may practically be stored in the reservoir 11. I have therefore designed modifications of my comb with the view of satisfying such requirements. 55

Fig. 1 discloses a dispensing comb having the same basic design as the one described above and shown in Fig. 2, except for modifications in the mechanism. The piston 14, instead of being attached directly to the spring 15, is joined to one end of a notched ratchet bar 142, the other end of the bar being attached to the spring 15. The bar is passed through a pawl shaped like a tennis racket frame 22, the handle of which 222, emerges on the outside of the comb. There is a spring coil 25 about the outside portion of the handle and a little overlapping button 223, at its terminus. The action of the spring 25, causes the pawl to normally engage the notched bar and prevent it from moving forward. If the button 223, is pressed the pawl disengages and permits the notched bar to move forward a desired known distance such as the distance between the faces of two or more ratchet teeth. Thus the volume of liquid which occupied the space through which the plunger regulatively moves may obviously be predetermined as may the whole quantity occupying the chamber, simultaneously permitting the pressure in the mechanism to be exerted upon the liquid.

Fig. 6 discloses a dispensing comb having no reservoir and no mechanism for the expulsion of the liquid. This comb dispenses liquid by way of gravity. A storage container 30, is suspended from a stand, ceiling or wall at a point above the comb. A suitable length of pliable hose 31, is attached, at one end, to the container, the other end slipped over the projecting nipple 32, of the comb. Regulating mechanism preferably in the form of a screw valve 136, or the like, intercepts the flow of liquid through the discharge channel. Turning the screw valve 136, one way or another regulates or stops the flow of liquid through the comb.

Whenever very fine distribution of the liquid used, is necessary, as for instance, in the case of hair coloring, I removably attach a fine toothed ordinary comb to my dispensing comb, one directly trailing the other. Said fine teeth aid the more minute distribution of the liquid.

As many apparently widely apparent embodiments of the invention could be devised without departing from the scope thereof it is intended that all matter contained in the above description or shown in the accompanying drawing shall be interpreted as illustrative and not in a limiting sense.

I claim:

1. A fountain comb comprising a body; a plurality of hollow teeth, open at each end, therewith; a cavity within the body leading to said teeth; and means normally automatically tending to expel a liquid, within the hollow comb, through the teeth at a single stroke.
2. A fountain comb comprising a body; a plurality of hollow teeth, open at each end, therewith; a cavity within the body leading to said teeth; means normally automatically tending to expel a liquid, within the hollow comb, through the teeth at a single stroke; and means for measuring the quantity of said liquid forced through said teeth.
3. A fountain comb comprising a body; a plurality of hollow teeth, open at each end, therewith; a cavity within the body leading to said teeth; and means normally automatically tending to expel a liquid, within the hollow comb, through the teeth at a single stroke; said means comprising a movable member.
4. A fountain comb comprising a body; a plu-

rality of hollow teeth, open at each end, therewith; a cavity within the body leading to said teeth; and means normally automatically tending to expel a liquid, within the hollow comb, through the teeth at a single stroke; said means comprising a plunger and actuating means for said plunger.

5. A fountain comb comprising a body; a plurality of hollow teeth, open at each end, therewith; a cavity within the body leading to said teeth; means whereby the liquid is forced into the cavity and ejected from the teeth of the comb at a pressure greater than the atmosphere; said means comprising a member having a conduit one end of which is normally higher than said comb and open to the atmosphere.

6. A fountain comb comprising a body; a plurality of hollow teeth, open at each end, therewith; a cavity within the body leading to said teeth; means whereby the liquid is forced into the cavity and ejected from the teeth of the comb at a pressure greater than the atmosphere; said means comprising a member having a conduit one end of which is normally higher than said comb; and a container connected with said end open to the atmosphere.

7. A fountain comb comprising a body; a plurality of hollow teeth, open at each end, therewith; a cavity within the body leading to said teeth; means normally automatically tending to expel a liquid, within the hollow comb, through the teeth at a single stroke; said means comprising a plunger and actuating means for said plunger; and means for moving said plunger in the opposite direction against said spring.

8. A fountain comb comprising a body; a plurality of hollow teeth, open at each end, therewith; a cavity within the body leading to said teeth; means normally automatically tending to expel a liquid, within the hollow comb, through the teeth at a single stroke; said means comprising a plunger and actuating means for said plunger; and a string for moving said plunger in the opposite direction against the spring.

9. A fountain comb comprising a body; a plurality of hollow teeth, open at each end, therewith; a cavity within the body leading to said teeth; means normally automatically tending to expel a liquid, within the hollow comb, through the teeth at a single stroke; and means mounted in the comb for regulating the rate of flow of said liquid.

10. A fountain comb comprising a body; a plurality of hollow teeth, open at each end, therewith; a cavity within the body leading to said teeth; means normally automatically tending to expel a liquid, within the hollow comb, through the teeth at a single stroke; and means mounted in the comb for regulating the rate of flow of said liquid at a plurality of different rates of flow.

11. A fountain comb comprising a body; a plurality of hollow teeth, open at each end, therewith; a cavity within the body leading to said teeth; means normally automatically tending to expel a liquid, within the hollow comb, through the teeth at a single stroke; and a member mounted in the comb comprising a cut-off of flow of liquid to said teeth.

12. A fountain comb comprising a body; a plurality of hollow teeth, open at each end, therewith; a cavity within the body leading to said teeth; means normally automatically tending to expel a liquid, within the hollow comb, through the teeth at a single stroke; and a member mounted in the comb comprising both a cut-off

of flow of said liquid to said teeth and a plurality of conduits of different size.

13. A fountain comb comprising a body; a plurality of hollow teeth, open at each end, therewith; a cavity within the body leading to said teeth; means normally automatically tending to expel a liquid, within the hollow comb, through the teeth at a single stroke; and a member mounted in the comb comprising both a cut-off 5 of flow of said liquid to said teeth and a plurality of conduits of different size; said member being mounted by screw threads in said comb.

14. A fountain comb comprising a body; a plurality of hollow teeth, open at each end, therewith; a liquid supplying reservoir having a connecting duct leading to a distributing channel connected to said teeth conduits; means normally automatically tending to expel a liquid, within the hollow comb, through the teeth at a 10 single stroke; and a member mounted in the comb comprising both a cut-off of flow of said liquid to said teeth and a plurality of conduits of different size; said member being mounted by screw threads in said comb.

25 15. A fountain comb comprising a body; a plurality of hollow teeth, open at each end, therewith; a cylindrical cavity within the body in communication with a passageway leading to said teeth conduits; a piston in said cylinder, operable by a spring through the entire length of the 30 cylinder normally tending to force all liquid within the cylinder through the teeth at a single stroke; and a multi-way valve to check said tendency and to predeterminedly vary the speed 35 of said forced liquid; said valve comprising a rotatable plug having an axial bore in communication with the cylinder and a plurality of lateral ports of different diameters communicating with the axial bore; said ports being separately registrable with 40 said passageway by the rotation of the rotatable plug; and means to move the piston in the opposite direction.

45 16. A fountain comb comprising a body; a plurality of hollow teeth, open at each end, therewith; a cylindrical cavity within the body in communication with a passageway leading to

said teeth; a spring operated piston in said cylinder normally tending to force all liquid within the cylinder through the teeth at a single stroke; and a multi-way valve to check said tendency and to predeterminedly vary the speed of said forced liquid; said valve comprising a rotatable plug having an axial bore in communication with the cylinder and a plurality of lateral ports of different diameters communicating with the axial bore; said ports being separately registrable with 10 said passageway by the rotation of the plug; and means for measuring the quantity of said liquid forced through the teeth.

17. A fountain comb comprising a body; a plurality of hollow teeth, open at each end, therewith; a cylindrical cavity within the body in communication with a passageway leading to said teeth conduits; a piston in said cylinder, operable by a spring through the entire length of the cylinder normally tending to force all liquid with the 20 cylinder through the teeth at a single stroke; a multi-way valve to check said tendency and to predeterminedly vary the speed of said forced liquid; said valve comprising a rotatable plug having an axial bore in communication with the 25 cylinder, and a plurality of lateral ports of different diameters communicating with the axial bore; said ports being separately registrable with said passageway by the rotation of the rotatable plug; and means to move the piston in the opposite 30 direction.

18. A fountain comb comprising a body; a plurality of hollow teeth, open at each end, therewith; a cylindrical cavity within the body in communication with a passageway leading to said teeth conduits; a piston in said cylinder, actuated by a spring through the entire length of the cylinder normally tending to force all liquid with the cylinder through the teeth at a single 35 stroke; and means mounted in the comb for regulating the rate of flow of said liquid at one of a plurality of different predeterminedly fixed rates of flow.

MOSES MARTON. 45
